FASTENER DRIVING MACHINE

James E. Merritt, Martinsville, Va.

Application January 30, 1948, Serial No. 5,311

4 Claims. (Cl. 1—25)

1

This invention relates to tacking tools, and more particularly to a tack inserting tool of the type adapted to carry a length of wire from which the tack is cut while it is being driven by the tool.

A main object of the invention is to provide a novel and improved tack injecting and cutting device which is very simple in construction, easy to operate, and wherein, by a simple adjustment of the device, the operating stroke thereof may be regulated.

A further object of the invention is to provide an improved tack cutting and driving device which involves only a few parts, is rugged in construction and which is manipulated by simple downward pressure applied to the device, whereby tacks may be driven in rapid sequence and with a minimum amount of labor, and wherein the length of the tack may be adjusted as desired.

Further objects and advantages of the invention will become apparent from the following description and claims and from the accompanying drawings wherein:

Figure 1 is a side elevational view, partly in cross-section, of a tack injector constructed in accordance with the present invention.

Figure 2 is a vertical cross-sectional view taken through the central vertical plane of the tack injector of Figure 1 and showing the positions of the parts at the completion of a tack driving operation.

Figure 3 is a top plan view of the tack injector of Figure 1.

Figure 4 is a vertical cross-sectional view taken on line 4—4 of Figure 1.

Figure 5 is a horizontal cross-sectional view taken on line 5—5 of Figure 4.

Figure 6 is an enlarged detail perspective view of a wire guiding member employed in the tack injector of Figure 1.

Referring to the drawings, 11 designates a generally tubular housing which is rectangular in cross-section and is formed at its bottom end with inwardly tapering walls terminating to define a reduced rectangular aperture 12 aligned with the vertical axis of housing 11. Designated at 13, 13 are opposing convergent inner wall surfaces of said inwardly tapering bottom walls. Secured to the top end of housing 11 is a flat rectangular cover plate 14 formed with a central aperture 15.

Slidably fitting in the lower portion of housing 11 is a hollow rectangular block or sleeve 16 and secured to opposing walls of said sleeve are spaced transverse pins 17, 17 said pins being respectively parallel to the inclined surfaces 13, 13 being located in a common horizontal plane and 55

2

being symmetrically spaced with respect to the vertical axis of housing 11. Pivotedly mounted on said pins 17, 17 are the respective lever arms 18, 18 the lower ends of said lever arms being formed with opposed cutting jaws 19, 19 and the upper end portions of said arms being formed with outwardly offset elements 20, 20. The outwardly offset elements 20, 20 are connected to the respective lever arms 18, 18 by downwardly and inwardly inclined opposing abutment portions 21, 21 and carry at their top ends downwardly and inwardly inclined opposed lug elements 22, 22.

Slidably positioned in the housing 11 adjacent 15 the offset elements 20, 20 are vertical plate members 23, 23' between which is secured a wedge block 24, said offset elements being movably received between the plate members 23, 23' on opposite sides of the wedge block 24. Wedge block 24 is formed at its bottom end with downwardly convergent wedge surfaces 25, 25.

When the lever arms 18, 18 are in the vertical positions shown in Figure 1, the downward inclination of the abutment portions 21, 21 is somewhat greater than the downward inclination of the wedge surfaces 25, 25, as shown in Figure 1. When block 24 is moved downwardly into engagement with abutment portions 21, 21, the block rotates arms 18, 18 outwardly to the positions shown in Figure 2 to equalize the inclinations of the abutment portions 21, 21 with the inclinations of the wedge surfaces 25, 25.

Wedge block 24 is formed at its top end with downwardly convergent wedge surfaces 26, 26 adapted to wedgily cooperate with the inclined lug elements 22, 22 responsive to upward force on wedge block 24 to urge the offset elements 20, 20 inwardly.

Wedge block 24 is formed with a vertical central bore 27 aligned with the vertical axis of housing 11. A wire blank 28 is adapted to pass slidably through bore 28, said blank being inserted through the aperture 15 in top cover plate 14.

At one side thereof adjacent its bottom end, housing 11 is formed with an aperture 29, said aperture being formed with an inner shouldered seat at 30. Formed in the opposing wall of housing 11 is a similar seat 31. Designated at 32 is a plate member formed adjacent its ends with depending flanges 33 and 34, said ends and flanges being adapted to be received in the respective seats 31 and 30, as shown in Figure 4, whereby plate member 32 is supported in a horizontal transverse position in the lower portion

of housing 11. A screw 35 is threaded through the shouldered portion of aperture 29 and passes through an aperture 36 formed in flange 34, thereby locking the plate member 32 in said horizontal transverse position. Plate member 32 is formed with a central aperture 37 and secured to the bottom surface of said plate member adjacent the flanges 33 and 34 are inwardly extending leaf springs 38, 39 terminating beneath the aperture 37.

The wire blank 23 passes through the aperture 37 of plate member 32 and is engaged by the opposing inner end edges of the leaf springs 38, 39, causing said springs to be flexed downwardly, as shown in Figure 4. The leaf springs thereby hold the wire blank against upward retraction but allow it to be moved downwardly by the action of jaws 19, 19 as will be presently described.

Adjacent plate member 23' the side wall of 20 housing 11 is formed with a vertical slot 39. Designated at 40 is a handle member having a threaded stud portion 41 which is slidably received in said slot for vertical movement therein and is threaded into plate member 23'. Secured to the side wall of housing 11 below and parallel to movable handle member 40 is a stationary handle member 42. A strong coiled spring 43 is seated at its ends in opposing recesses formed in handle members 40 and 42 and biases handle member 40 upwardly with respect to handle member 42.

Secured to the housing side wall above slot 39 is a lug 44 and threaded through said lug is a vertical wing bolt 45 which engages handle member 40 and acts to limit upward movement thereof caused by the biasing action of spring 43. The extent of downward travel per stroke of handle member 40 may therefore be regulated by suitably adjusting wing bolt 45.

Spring 43 normally maintains wedge block 24 in its raised position, shown in Figures 1 and 4. Since lug elements 22, 22 bear on the top surfaces 26, 26 of wedge block 24, sleeve 16 is also held in a raised position by spring 43, and the adjustment of wing screw 45 also predetermines the starting position of said sleeve member.

Block 16 is formed at opposite sides thereof with rectangular vertical recesses 46 and positioned in each recess is a friction shoe 47. Positioned between each shoe 47 and the inner wall surface of the associated recess 46 is a leaf spring 48 which biases the shoe outwardly into frictional engagement with the inner wall surface of housing 11, whereby a substantial force is required to move the block 16 vertically in the housing.

To operate the device, handle member 40 is forced downwardly toward handle member 42. The wire end is at this time in engagement with the surface of the member into which the tack is to be driven. As wedge block 24 comes into engagement with the abutment elements 21, 21, the arms 18, 18 are rotated outwardly and the jaws 19, 19 are moved inwardly to grip the wire 23. Continued downward movement of wedge block 24 forces the jaws 19, 19 into abutment with the surfaces 13, 13, the wire end being meanwhile driven into the underlying surface. The surfaces 13, 13 exert an inward wedging force on the jaws 19, 19 as downward movement of said jaws continues, and as the jaws reach the aperture 12, the jaw edges substantially meet and shear off the wire substantially flush with the underlying surface, as shown in Figure 2. Handle member 40 is then released, allowing spring 43 to expand.

This causes block 24 to move upwardly and releases the pressure on abutment elements 21, 21. The wire blank is held against upward movement by the leaf springs 38, 39 but the lever arms 18, 18 are free to be drawn upwardly since spring 43 is strong enough to overcome the frictional force exerted by the shoes 47. As the top surfaces 26, 26 engage the inclined lugs 22, 22 the lever arms are raised and at the same time rotated 10 inwardly, restoring the parts to the starting positions shown in Figures 1 and 4. Since the setting of wing bolt 45 determines the starting position of handle member 40, the length of the downward stroke of lever arms 18, 18 may thereby be regulated, and hence the length of the tack cut from wire 23 may likewise be controlled.

While a specific embodiment of a tack forming and driving tool has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a tack injecting tool of the type employing a wire blank for forming the tacks, a tubular housing having a bottom wall formed with an aperture, the bottom wall surfaces sloping downwardly and inwardly toward said aperture, a sleeve member slidably positioned in the lower portion of said housing, a pair of opposing depending cutting jaws pivoted to said sleeve member and engageable with the downwardly and inwardly sloping bottom wall surfaces of the housing, outwardly offset top arms carried by said cutting jaws, said top arms being formed with downwardly and inwardly extending abutment surfaces, and a block member slidably received in the housing between said offset top arms and formed with downwardly and inwardly inclined top surfaces wedgingly cooperable with said abutment surfaces, said block member being formed with a vertical bore through which the wire blank passes downwardly toward the cutting jaws.

2. In a tack injecting tool of the type employing a wire blank for forming the tacks, a tubular housing having a bottom wall formed with an aperture, the bottom wall surfaces sloping downwardly and inwardly toward said aperture, a sleeve member slidably positioned in the lower portion of said housing, a pair of opposing lever arms pivoted to said sleeve member, said arms being formed at their bottom ends with opposed cutting jaws engageable with the downwardly and inwardly sloping bottom wall surface and at their upper portions with outwardly offset elements, the top ends of said offset elements comprising downwardly and inwardly directed projections, a block member slidably received in the housing between said offset elements, the top of said block member being formed with downwardly convergent wedge surfaces wedgingly cooperable with said projections, said block member being formed with a vertical bore through which the wire blank passes, and means biasing said block member upwardly into engagement with said projections.

3. In a tack injecting tool of the type employing a wire blank for forming the tacks, a tubular housing having a bottom wall formed with an aperture through which the tacks are injected into a subadjacent surface, the bottom wall surfaces sloping downwardly and inwardly toward

said aperture, a sleeve member slidably positioned in the lower portion of said housing, a pair of opposing lever arms pivoted to said sleeve member, said arms being formed at their bottom ends with opposed cutting jaws engageable with the downwardly and inwardly sloping bottom wall surface of the housing, said arms being formed at their top ends with outwardly offset elements, the top ends of said offset elements comprising downwardly and inwardly directed projections, a block member slidably received in the housing between said offset elements, the top of said block member being formed with downwardly convergent wedge surfaces wedgingly cooperable with said projections, means biasing the block member upwardly, said block member being formed with a vertical bore through which the wire blank passes, an apertured plate secured in the lower portion of the housing through which said wire blank also passes, and downwardly and inwardly directed spring members carried by the end portions of said plate and engaging the wire blank on opposite sides thereof to oppose upward movement thereof and to limit the blank only to downward movement.

4. In a tack injecting tool of the type employing a wire blank for forming the tacks, a tubular housing having a bottom wall formed with an aperture through which the tacks are injected into a subadjacent surface, the bottom wall surfaces sloping downwardly and inwardly toward said aperture, a sleeve member slidably positioned in the lower portion of said housing, a pair of opposing lever arms pivoted in said sleeve member, said arms being formed at their bottom

35

ends with opposed cutting jaws engageable with the downwardly and inwardly sloping bottom wall surface of the housing, said arms being formed at their top ends with outwardly offset elements, the top ends of said elements comprising downwardly and inwardly directed projections and the lower portions of said elements comprising downwardly and inwardly inclined abutments, a block member slidably received in the housing between said offset elements and formed to wedgingly cooperate with said projections responsive to upward movement of said block member and with said abutments responsive to downward movement thereof, means biasing said block member upwardly, said block member being formed with a vertical bore through which the wire blank passes, an apertured plate secured in the housing subadjacent said sleeve member through which said wire blank also passes, and downwardly and inwardly directed leaf springs carried by the end portions of said plate and engaging the wire blank on opposite sides thereof to oppose upward movement thereof and to limit the blank only to downward movement.

25 JAMES E. MERRITT.
